UNITED STATES PATENT OFFICE.

ALEXANDER F. WINTERS AND ALVIN H. PORTER, OF GRAND RAPIDS, MICHIGAN,
ASSIGNORS TO WINTERS & STRYKER, OF GRAND RAPIDS, MICHIGAN, A FIRM
CONSISTING OF ALEXANDER F. WINTERS AND ALBERT STRYKER.

SAFETY APPLIANCE FOR PUNCH-PRESSES.

1,270,578.

Specification of Letters Patent. Patented June 25, 1918.

Application filed July 2, 1917. Serial No. 178,210.

To all whom it may concern:

Be it known that we, ALEXANDER F. WINTERS and ALVIN H. PORTER, citizens of the United States of America, residing at 5 Grand Rapids, in the county of Kent and State of Michigan, have invented certain new and useful Improvements in Safety Appliances for Punch-Presses; and we do hereby declare the following to be a full, 10 clear, and exact description of the invention, such as will enable others skilled in the art to which it appertains to make and use the same.

This invention relates to a safety guard especially applicable to punch presses and the like, the object and purpose thereof being to render it practically impossible for a workman to place his hands or fingers underneath the punch at any time during or 20 immediately previous to the downward movement thereof. At the same time it is designed that the guard shall act so that in the event of an undesired downward movement of the punch, the guard shall be in 25 place whenever this occurs to stop the entrance of the hand anywhere underneath the punch. A further object of the invention consists in the construction of the guard in a very simple and economical manner 30 and so that the same can be attached to a punch press without the necessity of machine work of any kind or character the guard as a whole being attached in a very short time. All of these objects and purposes as well as many others not particularly stated will appear as understanding is had of the construction shown in the accompanying drawings in which;

Figure 1 is a perspective view of a punch press equipped with our invention.

Fig. 2 is a horizontal section through the press a short distance above the bed thereof and showing the construction comprising the guard in plan view; and

Fig. 3 is a similar view in perspective.

Like reference characters refer to like parts throughout the several views of the drawings.

The punch press may be of ordinary construction including spaced housing castings 1, in front of which is located a horizontal table or bed 2 on which the die is secured. The ram 3 is slidably mounted above the

table between the housing castings and is operated by rotation of a shaft 4 on which 55 a wheel 5 is loosely mounted and which may be connected to the shaft by a pull on the chain 6 which operates the clutch for connecting the same. The chain at its lower end has connection with the foot lever 7, pivotally mounted at 8 on one of the housing castings. This structure is old and well known and is common to punch presses and as it in itself forms no part of the present invention is not described with any measure 60 of detail.

In the construction of the safety guard two brackets 9 and 10 are provided which are connected together by an interposed rod 11 oppositely threaded at its ends and 70 threading into the brackets. Lock nuts 12 are used to hold the brackets in any position to which they may be adjusted. The brackets are adapted to be located between the housing castings 1 a short distance above 75 the bed, and by operating the rod 11 they may be forced against the inner sides of the housing castings and, in this manner, securely attached in place.

A shaft 13 extends through the free ends 80 of the brackets and is rotatively mounted therein, one end carrying collar 14 between which and the end of the bracket 9 a torsion spring 15 is secured. At the opposite end of the shaft a second collar 16 is fixed, 85 from which a hook 17 projects adapted to connect with the upper link of a chain 18, which extends downwardly and carries a screw threaded pin or bolt 19 on its lower end threading through and in this manner 90 adjustably connected to a member 20 which may be attached, by means of the set screw shown in Fig. 1, to the foot lever 7.

A pair of blocks 21 are adjustably mounted on the shaft 13 between brackets 9 and 10. By operation of the nuts 22 the same may be fixed at any desired position on the shaft 13 and may be adjustable lengthwise of the shaft as well as at different angles with respect to the bed 2 below the shaft. 95 Each of these blocks has longitudinal slits in its upper side as indicated at 23 and set screws 24 thread through the parts of the blocks thereby clamping said parts against rods 25 which pass through the blocks as 100 shown and which are capable of adjustment 105

to a variety of positions with respect to the blocks. At their outer end rods 25 in turn carry blocks 26 between which a rod 27 is positioned. Blocks 26 are also of substantially the same structure as those shown at 5 21 to permit the adjustment thereof along the length of rod 27. Two posts 28 extend upwardly from blocks 26 between which a guard 29, preferably of heavy wire screen, 10 is secured.

In practice when the ram 3 is in uppermost position and the punch carried thereby is raised the torsion of spring 15 serves to rotate shaft 13 and the parts attached thereto are elevated, guard 29 occupying an upper position such that the workman may readily insert pieces of material to be operated upon by the punch and die. On depression of the forward end of the foot lever 7, shaft 13, 15 through the connecting chain 18, is rotated in the opposite direction and the guard is brought down on the bed 2 to its lowermost position before connection of the wheel 5 and shaft 4 takes place, it being understood 20 that it is at the limit of downward movement of the foot lever 7 that operation of the ram occurs. On release of the foot lever the guard automatically rises and on depression it is lowered and if, by mistake, 25 the operator should keep his foot on the foot lever, holding it in depressed position so that a second operation of the ram should take place, it would not be dangerous to the operator on account of the fact that the 30 guard is in place preventing any entrance of the hands of the operator to a point below the punch.

The construction outlined is relatively simple and in its attachment to a punch 40 press is particularly simple and useful. It is not necessary to alter in any respect the punch press structure nor is it necessary to bore any holes or do any machine work of any kind in order to attach the same to the 45 punch press. In operation the device is especially effective. Many changes in minor detail may be resorted to without departing from our invention and, accordingly, we do not wish to be limited other than is necessitated by the terms of the claims defining 50 the invention.

We claim:

1. A guard appliance for punch presses or the like adapted for application thereto 55 above the bed and between the vertical housing castings thereof, including spaced apart brackets adapted to extend in front of said housing castings, means to adjust said brackets with respect to each other to 60 thereby force them against the inner sides of the housing castings, a shaft rotatably mounted on the front ends of the brackets, a guard member fixed to and located in front of the shaft, means attached to the 65 shaft normally elevating the guard, and

means adapted to connect said shaft and the foot lever of the press to lower the guard on depression of said foot lever.

2. A guard appliance for punch presses or the like adapted for application thereto 70 above the bed and between the vertical housing castings thereof, including spaced apart brackets adapted to locate at their rear ends between said housing castings and extend in front thereof, means to adjust said brackets 75 toward or away from each other to thereby force them against the inner sides of said housing castings, a shaft rotatably mounted on the front ends of the brackets, rods connected to and extending in front of the 80 shaft, means for adjusting the rods toward or away from each other, a guard member attached to and located between the front ends of the rods, different lengths of guard members being used with different positions 85 of the rods on the shaft thereby adapting one size of appliance for different sizes of presses, means attached to the shaft normally turning the same to elevate the guard member, and means attached to the shaft 90 and adapted to be connected to the foot lever of the punch press to lower the guard member on depression of said foot lever.

3. A guard appliance for punch presses and the like, comprising a pair of spaced 95 brackets, a rod connecting the same and adjustable to vary the distance between the brackets whereby said brackets may be adjusted to bear against spaced apart vertical housing castings of a punch press, a shaft 100 rotatably carried by the brackets, means tending to rotate said shaft in one direction, a guard member positioned a distance in front of the shaft, means connecting the same thereto, and means for rotating the 105 shaft in the opposite direction to change the normal position of said guard member, substantially as described.

4. A guard appliance for punch presses and the like, comprising two spaced apart 110 brackets, means for adjusting the same toward or away from each other, adapting the same for attachment between the spaced apart vertical housing castings of a punch press, a shaft rotatably carried by said brackets, a torsion spring interposed between the shaft and one of the brackets tending to rotate the shaft in one direction, two blocks 115 connected to the shaft, a rod connected to each block and extending in front thereof, a block secured at the front end of each rod, a vertical rod on each block, a guard member interposed between and connected to said vertical rods, a hook projecting forward from one end of the shaft, and a flexible 120 connection attached to the hook adapted to be secured to the foot lever of the punch press, substantially as described.

5. A construction as claimed in claim 4 in which said blocks on the shaft are adjustable 130

thereon toward or away from each other, and said rods mounted on the blocks are adjustable thereon in the direction of their length, substantially as described.

5 6. In combination, a punch press including spaced apart vertical housing castings, a horizontal bed projecting forward therefrom, a ram mounted for vertical movements above the bed, driving means for the
10 ram normally disconnected therefrom, means including a foot lever for connecting the driving means to the ram to operate the same, two brackets interposed between the housing castings, means adjustably connecting the same and operable to force the brackets against the inner sides of the housing castings, a shaft rotatably carried by the brackets in front of said castings and above the bed, rods connected to and extending
15 forward from the shaft, a guard carried by and between the forward ends of the rods and extending a distance above said rods, yielding means tending to rotate the shaft

in one direction and elevate the guard above the bed, and means interposed between the 25 shaft and foot lever to rotate the shaft in the opposite direction and lower the guard on depression of said foot lever, substantially as described.

7. A guard appliance for punch presses 30 or the like adapted for application thereto above the bed and between the vertical housing castings thereof including supporting brackets and means to force them against the inner sides of said housing castings, a 35 guard member rotatably mounted on the brackets adapted to move up and down above the bed, means for elevating the guard, and means adapted to attach to the foot lever of the punch press to lower the 40 guard on depression of said foot lever.

In testimony whereof we affix our signatures.

ALEXANDER F. WINTERS.
ALVIN H. PORTER.
